UNITED STATES PATENT OFFICE.

REINHOLD EDER, OF BERLIN, GERMANY.

SEWING-MACHINE.

SPECIFICATION forming part of Letters Patent No. 623,534, dated April 25, 1899.

Application filed July 25, 1898. Serial No. 686,849. (No model.)

To all whom it may concern:

Be it known that I, REINHOLD EDER, machinist, a subject of the Emperor of Germany, and a resident of 13 Greifswalderstrasse, in 5 the city of Berlin, N. O., and Empire of Germany, have invented certain new and useful Improvements in Sewing-Machines, of which the following is a specification.

My invention relates to improvements in 10 those sewing-machines in which an eyed needle and a hook-needle are employed.

My improvements consist in novel features of construction hereinafter described and claimed.

15 In order that my invention may be fully understood, I will proceed to describe it with reference to the accompanying drawings, in which—

Figure 1 is a side elevation of my improved 20 sewing-machine. Fig. 2 is a front elevation of my sewing-machine, the loop-carrier being broken away and omitted. Fig. 3 is a detail view transverse of the machine, the needles, with the thread, being forced through the fabric and the loop conveyer and spreader ready 25 to seize the thread from the eyed needle. Fig. 4 is another view, the loop conveyer and spreader having taken the thread from the eyed needle and placed it around the hook-needle, and thus formed a loop beneath the 30 fabric. Fig. 5 is another view, the loop conveyer and spreader and needles having been returned to normal position and the needles having carried the ends of the loop with them 35 through the fabric. Fig. 6 is another view, the loop-carrier having placed the loop beneath the eyed needle. Fig. 7 is another view, the loop-carrier having been withdrawn and the eyed needle having entered the loop and 40 penetrated the fabric. Fig. 8 is a top view of a piece of fabric having a series of looped 45 stitches thus formed. Fig. 9 is a detail showing a top view of the loop conveyer and spreader. Fig. 10 is a detail showing a front view of the loop-carrier. Fig. 11 is a detail showing a side view of the loop-carrier. Fig. 12 is a detail plan view of the feed-bar shifter.

It has heretofore appeared impossible to 50 make by means of a machine tongue or looped stitches, such as buttonhole-stitching, called "languets," which resemble handwork. The languet, as at present well known, works with

several threads or produces chain or tambourstitches for connecting the cross-threads. Apart from the fact that these machines are 55 very complicated the machine-made languets do not appear so nice as those made by hand, and are for this reason in less demand than they should be, so that the main bulk of the said languets are still at present made by hand. 60

The machine which I have produced has in addition to great simplicity in construction the advantage that it forms a languet which has the appearance of a hand-made languet. My machine, as heretofore, is provided with 65 two needles, but works with only one thread, which the machine lays double above and below the fabric and forms only on one edge a quilting-stitch, as is the case in languets made by hand. 70

The essential part of the machine is the fabric-feeding device simultaneously working on both sides of the needles and the mechanism forming the stitch—that is to say, the eyed and hook needles in combination 75 with a loop-carrier and a loop conveyer and spreader. The thread-feeder only gives enough thread to the needles necessary to form a stitch, while the loop conveyer and spreader conveys the thread from the eyed 80 needle to the hook-needle beneath the fabric and the loop-carrier transfers the then formed loop again from the hook-needle to the eyed needle above the fabric and the eyed needle then stitches to the fabric the center of the 85 loop and continues down through the fabric to present the thread to the loop conveyer and spreader to form another loop.

1 is the bed-plate, 2 the hollow arm, and 3 the head of my improved sewing-machine. 90 The bed-plate 1 is formed with an opening 1^a, over and in which the stitching mechanism operates.

4 is a work-plate located over the opening, and 5 a piece of fabric being worked upon. 95

a is a cam-disk, and *a*² is a ratchet-wheel, with which the cam-disk is combined, mounted on a stud or center *a*³, secured to the side of the arm 2.

b is the driving-shaft, whereby the ratchet-wheel *a*² is rotated intermittently in the direction indicated by the arrow thereon. Secured to the driving-shaft is a cam-wheel *f*, formed with a cam-groove *f'*. 100

c is a lever having a longitudinal slot *c'* and pivoted at its lower end to the arm *2* and at its upper end connected with the cam-wheel *f* by means of a pin *c²*, working in the cam-groove *f'*.

g is a pawl or ratchet engaging the teeth of the ratchet-wheel and adjustable at its inner end in the slot *c'* of the lever *c* by means of a thumb-nut *g'*.

10 *d* is an upwardly-projecting lever pivoted at its lower end to the base of the arm and bearing by means of an antifriction-roller *d'* on the cams *a'* of the cam-disk *a*, whereby a vibrating movement is imparted thereto.

15 Pivoted at its inner end to the upper end of the lever *d* is a rack-bar *e*, reciprocating in and extending through the upper part of the head *3*, so as to mesh with a pinion *h²*, secured to the upper end of a sheath or sleeve *h'*, with

20 which the feeding device is connected. The rack-bar *e* imparts an oscillating movement to the sheath *h'* by means of the pinion *h²*. Within the sheath the needle-bar *h⁶* is supported and reciprocated by the usual supporting-bar *h⁷*.

25 *y'* is a collar to which is pivoted by its upper end the feed-bar *y*, provided with a foot *z*, which encircles the eyed needle *o* and hook-needle *h* and is adapted to move the fabric. This pivoting of the feed-bar

30 permits the foot to move, as indicated by the arrows, so as to feed the fabric to the machine. The inward movement of the feed-bar is imparted by means of a crank-lever *x*, pivoted to the head and having its inner arm provided with a pin *x'*, bearing against the feed-bar, and its outer arm engaged by a projection *v²* on a slide-bar *v*. The feed-bar is pivoted at its upper end to a projection *x²* on

35 a vertically-reciprocating slide *x²*, connected with the driving-shaft. The outward movement of the feed-bar is accomplished by a spring *z'*, also secured to the head. The sheath *h'* is, as previously stated, oscillated by connection with the cam-disk *a*.

40 *i'* is a ring or yoke secured to the feed-bar and surrounding the sheath.

45 *i²* is a disk plate located within an oblong opening *p'* in the ring, within which is an angular block *h³*, mounted on the sheath.

50 To the angular block *h³* is pivoted a lever *h⁴*, whose lower arm engages in a recess *i³* in the disk plate, so as to rotate it with the sheath and disk plate and whose upper arm bears on

55 a cam-block *h⁵*. A downward movement of the cam-block *h⁵* will impart to the feed-bar, through the lever *h⁴* and ring or yoke, an auxiliary feed movement in addition to the feed movement imparted by the lever *x*. The direction of this auxiliary feed movement will depend upon the relative position of the lever *h⁴*, which is controlled by the cam-disk *a* through the medium of the lever *d*, link *e*, and sheath *h'*, on which the lever is supported.

60 65 Through this feed mechanism it is apparent that the line of stitching may be curved. The shape of the curve depends upon the form of

cam-disk. In all the movements of the disk the feed-bar swings at each stitch toward and away from the direction of stitching. The 70 thread-feeder *i* is also operated by the driving-shaft *b*. For this purpose the thread-feeder bears by means of a roller *k* on a cam-disk *l*, mounted on the driving-shaft *b* in such a way that at one rotation of the driving-shaft *b* the 75 thread-feeder is moved once forward and swung backward, whereby as much thread is drawn off the spool as is necessary for forming one stitch. As previously stated, two 80 needles are employed in forming a stitch—to wit, an eyed needle *o*, in which the thread is threaded, and the other a hook-needle *h* for seizing the loop, both of which perforate the material in common.

m is the loop conveyer and spreader, which 85 conveys the thread from the eyed needle to and around the hook-needle and places it in the hook of the hook-needle. The loop conveyer and spreader works from the right to the left and comprises two parts *m'* and *m²*. 90 The loop conveyer and spreader *m* is located normally in front of the eyed needle between the latter and the thread and draws the thread when it swings forward toward the hook-needle. The head carries the pivoted jaw *m²*, 95 which has the action of laying the thread around the hook and which is adapted to rest closely to the head *m'* in normal position, and thus lay inside the loop of the thread.

m² is an adjustable plate projecting in the 100 path of the heel of the pivoted jaw, so as to open it and draw apart the loop of the thread, which is thus stretched across the hook-needle, lays it around the latter, and deposits it in the hook thereof. When the needle-bar 105 ascends, the needles carry the ends of the loop through the fabric and a loop-carrier *n* takes the inner end of the loop of the thread from the hook of the hook-needle *h* and transfers it over the fabric to a position beneath the 110 eyed needle, then withdraws, and the eyed needle passes down through the folded end of the loop, thus securing the adjacent sides of the loop. The loop-carrier consists of a pair 115 of jaws or forceps *n'*, which are pivoted to a 115 swinging rod *p*, hinged to the head of the machine and which is adapted to swing to and fro. This to-and-fro swinging of the rod *p* takes place by means of a roller *q*, traveling in the cam-groove *r'* of a cam-disk *r*, mounted on the driving-shaft *b* and connected by 120 links *r²* *r³* with the swinging rod *p*. On the rotation of the driving-shaft *b* the jaws *n'* are moved forward and backward. When the 125 jaws have reached their farthest forward point and the eyed needle is admitted within the loop, they are opened in order to permit them to withdraw past the eyed needle. This opening of the jaws takes place by means of a cam *s*, secured to the slide-bar *v*. This 130 cam passes between the inner ends *t* of the jaws and forces the outer ends of the jaws apart. When these jaws have again returned and the slide-bar *v* commences to rise, the

cam s moves away from the inner ends of the jaws and the jaws are closed by means of the springs u .

In operation the eyed needle o and the hook-needle h enter the fabric 5 and the eyed needle carries the thread with it. (See Fig. 3.) The thread-feeder then swings forward, and at the same time the loop conveyer and spreader commences to swing forward.

- 10 The loop-conveyer-and-spreader head m and pivoted jaw m^2 then push themselves between the eyed needle and the thread and carry the thread which has been delivered by the thread-feed i to the hook-needle. The heel of the pivoted jaw comes against the plate m^3 and opens the pivoted jaw, spreads the thread, and places the loop of the thread across the hook-needle. (See Fig. 4.) The needles rise again, the hook of the hook-needle carrying with it the loop of the thread which has been laid around the hook-needle by the loop conveyer and spreader. At the same time the loop conveyer and spreader m moves backward into its initial position. (See Fig. 5.)

25 The loop-carrier then commences to move forward and the closed jaws push themselves, with their point, into the loop of the thread, remove this loop from off the hook of the hook-needle, and carry it to the eyed needle. (See Fig. 6.) In the meantime the feeding device has moved the fabric one stitch farther forward, the eyed needle once more stitches within the loop and fastens the latter to the fabric. On the descent of the slide-bar v the cam s has passed between the inner ends of the jaws n' and opened the latter, and by the rotation of the driving-shaft b the loop-carrier has been drawn back. (See Fig. 7.) The stitch described is now finished and the

40 machine stands again in its initial position for another stitch.

Fig. 8 shows the appearance of a piece of material provided with a series of languet or loop stitches, from which it may be seen without further explanation what appearance the stitches have and how they are formed.

45 Having thus described my invention, the following is what I claim as new therein and desire to secure by Letters Patent:

50 1. A sewing-machine, comprising a needle-bar adapted to receive and to reciprocate an

eyed needle and a hook-needle, a loop conveyer and spreader located beneath the work-plate, having a pivoted jaw and adapted to place the thread from the eyed needle around the hook-needle, means for opening the pivoted jaw of the loop conveyer and spreader and a swinging bar located above the work-plate provided with a loop-carrier adapted to transfer a loop from around the hook-needle to a point beneath the eyed needle; substantially as described. 55

2. A sewing-machine, comprising a needle-bar adapted to receive and to reciprocate an eyed needle and a hook-needle, a loop conveyer and spreader adapted to place the thread around the hook-needle and a swinging bar located above the work, provided with a loop-carrier consisting of a pair of pivoted spring-jaws adapted to transfer a loop from 60 around the hook-needle to a point beneath the eyed needle, and a slide-bar carrying a cam-plate adapted to pass between the inner ends of the jaws to open the latter to permit them to withdraw from the eyed needle; substantially as described. 70

3. A feeding device comprising a needle-bar, an oscillating sheath surrounding the needle-bar, the slide-bar having an arm, a cam-block sleeved to the sheath and supported 80 in the arm, an angular block surrounding the sheath, the disk plate within which the angular block extends, the vertically-reciprocating slide, the feed-bar pivoted to the slide, a ring secured to the feed-bar and surrounding the 85 disk plate, the crank-lever having one arm engaged by the slide-bar and the other arm bearing against the feed-bar to cause the inward movement of the latter, a spring for causing the outward movement of the feed- 90 bar; substantially as described. 95

In witness whereof I have hereunto signed my name, this 13th day of July, 1898, in the presence of two subscribing witnesses.

REINHOLD EDER.
